COMBINATION CARPET AND LINOLEUM CUTTER

John S. Davis, 5942 N. Haven Drive,
North Highlands, Calif.

Filed Sept. 7, 1965, Ser. No. 86,868

Term of patent 14 years

(Cl. D54—13)

FIGURE 4 is an end view of the handle end; and,

I claim:

The ornamental design for a combination carpet and linoleum cutter, as shown.
